UNITED STATES PATENT OFFICE

ANDREW J. MONROE AND GEORGE W. MONROE, OF ARTHUR, ILLINOIS

ROAD PLANER

Application filed September 6, 1929. Serial No. 390,774.

The object of this invention is to provide, in a road planer having a plurality of longitudinally extending diverging elements or scraping blades, a rear blade, or slicer, adapted to extend transversely at a suitable angle and spread the material moving rearwardly between the diverging elements.

A further object is to provide special means for mounting and controlling the rear blade, so that its position may be changed with reference to the diverging elements, and said third blade, or rear transverse blade, may be caused to extend laterally to a greater distance on one side than on the other side.

15 A further object is to provide for changing the angular position of the slicer, or third blade, with reference to the path of travel of the machine.

With the foregoing and other objects in view, the invention consists in the novel construction and arrangement of elements disclosed, it being understood that modifications may be made within the scope of the claims without departing from the spirit of the invention.

In the drawings forming part of this application:—

Figure 1 is a perspective view of the machine.

30 Figure 2 is a view in top plan.

Figure 3 is a view in side elevation, showing the rear portion of the machine, slightly modified.

Figure 4 is a plan view of the form of the device shown in Figure 3 including means for changing the angular position of the rear element termed a slicer.

Figure 5 is a detail view, in perspective, showing a latch for retaining an adjusted position of the frame for the third blade or slicer.

The frame of the machine includes the side bars or channels 10 and 11, and a rear transverse bar 12, and this frame is to be mounted on an axle 13 carrying wheels 14.

A bail-shaped frame 15 extends rearwardly from the main portion of the machine and is mounted for swinging movement as shown at 16. This frame may be raised or lowered by means of the mechanism illustrated, and

including a chain or flexible device 17 connected with the forked member 18, the latter mounting, if desired, a pulley wheel 19 for chain 20, the latter passing around an upper pulley 21, and passing thence downwardly to a winding drum or roller controlled by a hand wheel such as wheel 22.

The diverging blades or scraping blades are designated 24 and 25 and are to be mounted in any suitable manner. The rear blade 60 or slicer is designated 27, and is mounted by means of the frame of U-form, and including the downwardly extending portions 28, the side portions 29 and the forward curved portion 30. This frame just referred to is 65 mounted for pivotal movement about the central vertical pin 33, and a latch including the retaining and releasing element 34 retains the frame for the rear blade, and said blade, in the position desired with reference 70 to a plane extending transversely of the machine and perpendicularly of the path of travel.

The latch 34 engages any of the apertures 75 30' of element 30. The frame 15 adapted to swing about a horizontal axis defined by transverse bar 16, is also adjustable laterally on said element 16, and an adjusted position is retained by means of a pin 16' adapted to pass thru an aperture in a laterally extending portion 15' and thru any of the apertures 16'' of bar 16.

In the modification shown in Figure 4, the lateral adjustment last indicated is effected by means of the particular construction now 85 to be described.

The third blade 27' carried by frame 40 is movable about a vertical axis defined by pin or the like 33' and rigid with the latter is a worm wheel 41 controlled by worm 42 90 and worm shaft 43 having universal connection with bar 44 similarly connected with shaft 45 controlled by hand wheel 46. In this form of the construction, transverse bar 48 has a portion 49 thereof threaded and internally threaded element 49' receives said bar, the latter being rotated as by means of gear wheels 50 and 51, shaft 52 and hand wheel 53.

A plurality of adjustments are therefore 100

provided for the third blade extending transversely with reference to the diverging blades 24 and 25, and it may be added that the elevation of the latter is controlled thru lifting chain 60 and drum 61, the latter being rotated by means of hand wheel 62. The adjustments of the third blade include that about pivot 33 or 33', and the vertical movement of the swinging frame to which the rear blade-holding frame is connected in the manner described. As previously stated, the swinging frame is adjustable by hand or adjustable mechanically, along bar 16, or the corresponding bar of Figures 3 and 4, and the slicer blade or rear blade 27 may therefore be placed in all of the positions required for effective work, as compared with the position of the bars 24 and 25.

What is claimed is:—

- 20 1. In a machine of the class described, a main frame, a plurality of diverging blades, a rear transversely extending blade constituting a slicer, a second frame mounting the rear blade, a bar for mounting the second frame for swinging movement at the rear of the frame first named, the swinging frame being slidable along the bar and transversely of the machine, means determining the elevation of the swinging frame, and means for retaining an adjusted position of the swinging frame on said bar.
- 25 2. In a machine of the class described, a main frame, a plurality of diverging blades, a rear transversely extending blade constituting a slicer, a second frame mounting the rear blade, a bar for mounting the second frame for swinging movement at the rear of the frame first named, the swinging frame being slidable along the bar and transversely of the machine, means determining the elevation of the swinging frame, and means for mechanically effecting and retaining an adjusted position of the second frame on said bar.
- 30 3. In a machine of the class described, a main frame, a plurality of diverging blades, a rear transversely extending blade constituting a slicer, means for mechanically changing the angular position of the rear blade by movement thereof about a vertical axis, a second frame mounting the rear blade, a bar for mounting the second frame for swinging movement at the rear of the frame first named, the swinging frame being slidable along the bar and transversely of the machine, means determining the elevation of the swinging frame, and means for retaining an adjusted position of the swinging frame on said bar.
- 35 4. In a machine of the class described, a main frame, a second frame mounted for swinging movement on a transverse axis, means for mechanically shifting the second frame in the direction of said axis, a third frame, means for mechanically varying the

angular position of the third frame with reference to the longitudinal axis of the machine, diverging blades carried by the main frame, and a slicer blade carried by the third frame and adapted to assume different angular positions with reference to the blades first named.

In testimony whereof we affix our signatures.

ANDREW J. MONROE.
GEORGE W. MONROE.
